UNITED STATES PATENT OFFICE.

RICHARD M. COLLARD, OF NEW YORK, N. Y., ASSIGNOR TO LEROY W. FAIRCHILD, OF SAME PLACE.

PENCIL.

SPECIFICATION forming part of Letters Patent No. 291,297, dated January 1, 1884.

Application filed July 2, 1883. (No model.)

To all whom it may concern:

Be it known that I, RICHARD M. COLLARD, of the city, county, and State of New York, have invented certain new and useful Improvements in Pencils, of which the following is a specification.

My invention has relation to that class of pencils in which the lead is held in a longitudinal movable carrier, which can be propelled so as to project the point of the lead the requisite distance beyond the tip or nozzle of the pencil-case. In a pencil of this kind the end of the lead is inserted and fitted tightly in the carrier, and after one lead is used up it is ordinarily somewhat difficult and troublesome to remove from the carrier the stub of lead remaining, which must be taken out before a fresh lead can be inserted. It is the object of my invention to obviate this difficulty and to provide a means whereby the lead can, whenever desired, be conveniently and quickly ejected from its carrier. To this end I combine in the carrier an expansible holder-tube in which the lead is inserted, and a presser-tube surrounding said holder-tube and adapted to contract and compress the latter, so as to cause it to clamp the lead, the two tubes being longitudinally movable with respect to one another, so as to permit the holder-tube to be projected far enough beyond the end of the presser-tube to expand and release the lead. With these two instrumentalities I combine an ejecting-spring, located within the holder-tube, and in such position that it will be compressed by the lead when the latter is pushed home to its place in the carrier. Thus when the lead is inserted in place it compresses the ejecting-spring, but at the same time is, by the clamping action of the presser-tube upon the holder-tube, held in place against the stress of said spring, so that as long as the two tubes move together the lead can be propelled in one direction or the other in the pencil-case, as usual; but if one of the tubes—for instance, the presser-tube—be held stationary and the other one be pushed forward, so as to project its expansible end beyond the presser-tube, then the lead will no longer be clamped, the ejecting-spring will be free to retract, and in so doing will eject forcibly the lead from the carrier. I also in practice combine with the three elements hereinbefore

named a retracting-spring, which tends to hold the two tubes in the position which they should occupy when clamping the lead.

The nature of my improvements and the manner in which the same are or may be carried into effect will be readily understood by reference to the accompanying drawings, in which I have represented the same as applied to a pencil in which the carrier is propelled by means of a spirally-slotted propelling-sleeve, rotatable with respect to the carrier, which is engaged by a stud or projection on the carrier.

Figure 1 is a longitudinal central section of the pencil. Fig. 2 is an elevation of the same with the outer case or sheath removed in order to show the spirally-slotted propelling-sleeve. Fig. 3 is a longitudinal central section of the front portion of the pencil, showing the parts of the carrier in the position they occupy when the lead stub is ejected. Fig. 4 is an elevation of the carrier detached, with the parts in normal position. Fig. 5 is a like elevation with the parts in the position they occupy when the two tubes are moved against the stress of the retracting-spring far enough to project the end of the holder-tube beyond the presser-tube.

The lead-carrier A is contained in a longitudinally-slotted guide-tube, B, in which it can slide freely. The guide-tube B carries at its front end the tip or nozzle B', which may be detachably united to said tube by a screw-connection, as shown. Between shoulders y y' on the slotted guide-tube is confined the spirally-slotted propelling-sleeve C, which is capable of rotary movement only on said guide-tube. To the propelling-sleeve is fixed the outer case or sheath, D, which is the pencil-handle. A stud, a, from the carrier A projects through the straight slot b of the guide-tube into the spiral slot c of the propelling-sleeve. By taking hold of the handle D with one hand and the nozzle B' with the other hand, and rotating the two relatively to one another, the carrier will be advanced or retracted, according to the direction of rotation.

A pencil of the foregoing general construction and mode of operation is old and not of my invention. I now proceed to point out those features in which my invention resides.

The characteristic features of the invention

have been indicated by me in the first part of this specification. Their preferred embodiment is represented in the drawings, and will now be described.

5 The holder-tube is lettered *d*. It is slotted at its front end, with a view to render it expansible, and is intended to receive the end of the lead *x*.

Surrounding the holder-tube is the presser tube *e*. These two tubes are longitudinally movable with respect to one another, and the outer or presser tube is of such diameter that when the lead is inserted in the holder-tube and the latter is drawn back into the presser tube the said holder-tube will thereby be caused to clamp or close tightly upon the lead.

Within the holder-tube, and located at its rear, is the ejecting-spring, hereinbefore referred to, consisting in this instance of a spiral spring, *f*, held at its rear end in place in the holder-tube by a suitable cross-pin or other fastening device. This spring is so placed that when the lead is pushed home to its place in the holder-tube it will thereby be compressed, as indicated in Fig. 1, the holder-tube normally clamping the lead with sufficient power to resist the outward push which the compressed spring exerts on the end of the lead. The stud *a*, hereinbefore referred to, is attached to the inner or holder tube, *d*.

Normally, when the spirally-slotted propeller-sleeve rotates, the two tubes *d e*, which form the body of the carrier *A*, move together, so as to advance or retract the lead. When, therefore, it is desired to eject the lead from the carrier, it becomes necessary that the one tube should be held still, while the other is moved in the proper direction to unclamp the lead. A convenient device for this purpose is found in a stop which, at the proper point shall prevent the further forward movement of the outer or presser tube. Such a stop can manifestly be constructed and arranged in various ways. In the present instance it is composed of an annular external shoulder or projection, *g*, on the presser-tube, and a corresponding internal shoulder or projection, *g'*, at the front end of the guide-tube *B*.

The parts of the carrier move bodily and together until the two shoulders *g g'* abut against one another, thus preventing further forward movement of the presser-tube. If, now, the stud *a*, by the action of the propelling sleeve, be carried fartherforward, the effect will be to push forward the holder-tube alone, and as soon as this tube has moved far enough beyond the presser-tube to unclamp the lead the ejecting-spring asserts itself, and by its recoil forcibly ejects the lead from the carrier and out through the nozzle, *B*, thus discharging it from the pencil.

In Fig. 3 the parts of the carrier are represented in the position which they occupy immediately after the discharge of the lead in the manner just indicated.

With a view to maintaining the parts of the carrier in a definite position, and of maintain-

ing the holder-tube normally in a position to clamp the lead, I make use of a spring, *h*, hereinbefore termed a "retracting-spring." 70 This spring surrounds a stem or prolongation, *d'*, of the holder-tube, which extends rearwardly through and beyond the presser-tube *e*. The stud *a* is on the rear end of this stem, and the retracting-spring is confined between 75 a pin or shoulder on the stem at the rear and the rear end of the presser-tube at the front, the arrangement being such that the retracting-spring thus confined tends to maintain the holder-tube *d* retracted within the presser-tube. A stop, *d''*, limits the extent to which the holder-tube can be drawn rearwardly by the retracting-spring. When, in the operation of ejecting the lead, the holder-tube is pushed forward beyond the presser-tube, the 80 retracting-spring is necessarily compressed. As soon, however, as it is free to recoil it at once returns the parts to normal position.

In order to insert a fresh lead, the lead, while the parts are held in the position shown 90 in Fig. 3, is inserted and pushed home in the carrier, and hold of the hand on the sheath *D* or nozzle *B'* is then loosened sufficiently to allow the retracting-spring to recoil, inward pressure on the lead being maintained until 95 the holder-tube closes tightly on the lead.

Having described my improvements and the best way now known to me of carrying the same into practical effect, what I claim as new and of my own invention is— 100

1. The combination, with the holder and presser tubes, movable with relation to one another for the purpose of clamping and releasing the pencil-lead, of an ejecting-spring located in the holder-tube in position to be 105 compressed by the lead inserted in said tube, substantially as and for the purposes hereinbefore set forth.

2. The combination, with the holder and presser tubes, movable relatively to one another for the purpose of clamping and releasing the pencil-lead, of an ejecting-spring located in the holder-tube in position to be compressed by the lead inserted in said tube, and a retracting-spring which normally holds said 115 tubes in a position in which they clamp and hold the pencil-lead in place against the stress of the compressed ejecting-spring, substantially as hereinbefore set forth.

3. The combination, with a pencil case or 120 sheath, a lead-carrier longitudinally movable therein, having a lead-holding socket composed of holder and presser tubes longitudinally movable with respect to one another, and an ejecting-spring in the holder-tube, as described, and means for propelling said carrier in said case, of a stop by which the forward motion of the outer or presser tube is limited, substantially as and for the purposes hereinbefore set forth.

4. The lead-carrier consisting of the presser and holder tubes, combined with ejecting and retracting springs, substantially as hereinbefore described, in combination with the pen- 130

oil-case, in which the carrier is movable longitudinally, means for propelling said carrier therein, and a stop to limit the forward movement of the presser tube, these instrumentalities being combined and adapted to co-operate substantially in the manner and for the purposes hereinbefore set forth.

5. The straight-slotted guide-tube, the spirally-slotted rotary propelling-sleeve, and the lead-carrier longitudinally movable in said guide-tube, and composed of the presser and holder tubes, combined with ejecting and retracting springs, substantially in the manner hereinbefore described, in combination with a

pin or projection on said holder-tube, which 15 extends through the straight slot of the guide-tube into the spiral slot of the propelling-sleeve, and a stop arranged and operating to arrest the forward movement of the presser-tube at a predetermined point, substantially 20 as and for the purposes hereinbefore set forth.

In testimony whereof I have hereunto set my hand this 27th day of June, 1883.

RICHARD M. COLLARD.
